ROTARY ELECTRIC SWITCH

George J. Meuer, Milwaukee, and Ralph A. Miller-
master, Whitefish Bay, Wis., assignors to
Cutler-Hammer, Inc., Milwaukee, Wis., a cor-
poration of Delaware

Application November 13, 1944, Serial No. 563,132

23 Claims. (Cl. 200—6)

This invention relates to improvements in rotary electric switches.

A primary object of the invention is to improve the construction and the operating characteristics of switches of the aforementioned character.

Another object is to minimize the number of different parts required to produce a rotary electric switch.

Another object is to facilitate assembly of the switch parts and to insure substantial dust-tightness thereof when assembled.

Another object is to provide unusual flexibility in the manner in which the switch parts may be assembled, whereby a large variety of desired circuit controlling characteristics of the completed switches may be attained.

Another object is to provide parts of simple form which may be combined to form switches of either single-pole or multi-pole type.

Another object is to provide for use of a novel and extremely shallow or wafer-form of molded insulating base to house each pole of the completed switch.

Another object is to provide novel and simple means for constructing a rotary switch having from two to eight different operative positions.

Another and more specific object of the invention is to provide a single rotary switch which may be of the eight-position, multi-pole type to afford control of as many as thirty-five or more electric circuits.

Another object is to provide combined contact and terminal members of novel form, the terminal portions of which are exposed and readily accessible at the exterior of each base.

Another object is to provide indexing means of novel form which also acts to provide for movement of the movable switch parts from each operative position thereof to another with a quick action.

Another object is to provide novel means for uniting the parts of such a switch of either the single-pole or multi-pole type, and novel means for mounting the switch as a whole.

Another object is to provide a novel form of element to substitute for each terminal member, when omitted, to insure maintenance of a substantially dust-tight condition of the completed switch.

Another object is to provide a novel form of insulating carrier for the rotatable contactor associated with each insulating base.

Another object is to provide different forms of contactors adapted for alternative use with the

respective carriers, according to the particular character of circuit commutation desired.

Another object is to provide a novel form of operating knob, and a novel form of attachment thereof to the operating shaft of the switch.

Another object is to provide parts of novel form and arrangement to provide either a single-pole or multi-pole switch of relatively small size or dimensions but of relatively high current controlling capacity.

Another object is to provide a molded insulating base having recesses of novel form therein to house and support the resilient stationary contacts and the contactor of the switch.

Various other objects and advantages of the invention will hereinafter appear.

The accompanying drawings illustrate certain embodiments of the invention which will now be described, it being understood that the embodiments illustrated are susceptible of modification within the scope of the appended claims.

In the drawings,

Fig. 1 is a side elevational view (actual size) of a three-pole, binding screw type of rotary electric switch; said switch being of the single-break type, and the same having eight operative positions; namely, seven "on" positions and one "off" position.

Fig. 2 is a top plan view of said switch, with the knob and a part of the one-hole mounting means removed.

Fig. 3 is an enlarged vertical sectional view, on the line 3—3 of Fig. 2.

Fig. 4 is a sectional view, on the line 4—4 of Fig. 3.

Fig. 5 is a greatly enlarged fragmentary plan view showing the form of one of the eight like recesses in each insulating base for accommodating a wiring terminal portion of the binding screw type (Figs. 3 and 7), or for alternatively accommodating a rubber plug or closure member of the form illustrated in Fig. 10.

Fig. 6 is a plan view of an external vertical connector or bus member, which may be employed in conjunction with any three vertically aligned binding screws of the switch.

Fig. 7 is a sectional view, on the line 7—7 of Fig. 3, showing the lower insulating base with the switch parts in assembled relationship thereto; the collector ring portion being broken away from its terminal and shown in dotted outline.

Fig. 8 is an exploded perspective view showing the relationship of the insulating carrier, the contactor, the collector ring, and a stationary

contact into and out of engagement with which the contactor is adapted to be moved.

Fig. 9 is a sectional view, on the line 9—9 of Fig. 3, showing the stationary stop plate and the movable stop plate for cooperation therewith.

Fig. 10 is a perspective view of a rubber plug which may be employed to seal the outer end of one of the base recesses when a combined contact and terminal member is omitted.

Fig. 11 is a top plan view of a modified form of molded insulating base showing four solder-lug type combined contact and terminal members arranged for cooperation with a special form of contactor to provide a double-break switch having an "off" position and three "on" positions.

Fig. 12 is a vertical sectional view, on the line 12—12 of Fig. 11; but showing a fragment of the metal cover member and certain parts associated therewith, and a fragment of a lower pole of the switch.

Fig. 13 is a perspective view of the special form of double-break contactor shown in Figs. 11 and 12.

Fig. 14 is a plan view of the developed, or blank, form of the lug-type stationary contact of Figs. 11 and 12; the points at which the blank is bent or reflexed being indicated by dotted lines.

Fig. 15 is a plan view of the cooperating stationary and movable stop plates as employed for the four-position switch of Figs. 11 and 12; additional lugs being provided, which lugs may be removed (as indicated by dotted lines) to afford proper stops for two to eight position switches, when desired.

Fig. 16 is a top plan view of a modified form of metal cover member which may be employed when a ninety-degree indexing switch is desired to afford a greater spacing of the stationary contacts of the switch.

Fig. 17 is a perspective view of a modified form of double-break contactor which is functionally like that shown in Figs. 11, 12 and 13 and which may be substituted therefor with advantage.

Fig. 18 is a perspective view of a terminal extension member employed upon a binding screw terminal type of switch to provide for rear wiring thereof.

Fig. 19 is a plan view of an insulating plate attached to the lower face of a switch base and cooperating with extensions of the character illustrated in Fig. 18 to assist in positioning the latter, and

Fig. 20 is a horizontal sectional view through the knob, on the line 20—20 of Fig. 1.

Referring first to the form of our invention shown in Figs. 1 to 10, inclusive, the numeral 25 designates an extremely shallow recessed base molded from a suitable insulating material, such as "Bakelite." When a three-pole switch is desired, as shown in Figs. 1 and 3, three of the bases 25 are employed. It is, of course, to be understood that the number of poles provided in the switch may vary from one to a much larger number. For practical reasons, however, not more than twelve poles are usually provided in a rotary switch of the character herein disclosed.

When two or more of the bases 25 are employed in a switch the same are initially of identical form; each base including a centrally located substantially circular recess 26, and a concentric substantially circular sub-recess 27 whose lower end is closed by an integral relatively thin diaphragm 28. Diaphragm 28 is removed, preferably by broaching, from all of the bases 25 except the lowermost base of each switch, to pro-

vide clearance for insertion and rotation of the polygonal portion 29 of the shaft; said portion preferably being of square form in transverse cross section, as best illustrated in Figs. 4, 7 and 9.

5 The sub-recess 27 in each base 25 is formed in part by an integral annular downward extension 30, and in part by an annular upward extension 31 formed integrally with the bottom wall of recess 27. The flat upper surface 32 of upward extension 31 forms a bearing for the flat lower surface of a carrier member 33 formed of a suitable insulating material, such as the material sold under the trade name of "Melmac." Member 33 is preferably of circular contour, as best illustrated in Fig. 8, and the same is provided centrally thereof with a rectangular opening 34 to accommodate with a rather close sliding fit the shaft portion 29, whereby said carrier is constrained to rotate with the shaft. An upstanding flange 35 surrounds and forms a part or extension of opening 34. Carrier 33 is also provided at its periphery with a series of eight equally spaced integral upstanding studs 36 which thus provide therebetween a corresponding number of equally spaced grooves or slots 37. As shown in Fig. 8, an alternate four of the eight slots 37 are preferably arranged to extend in directions at right angles to the planes of the four respective sides of opening 34, and the other alternate slots extend in planes radial to the four corners of said opening.

20 Carrier 33 is adapted to accommodate, in any one of eight different angular positions, a contactor which may be of the single-break type shown at 38 in Figs. 3, 7 and 8. As best illustrated in Fig. 8, contactor 38 is provided with an annular portion 39 adapted to fit between the peripheral studs 36 and opening 34; said portion preferably having an inner edge portion or opening 40 shaped as shown to fit around or accommodate the upstanding flange 35 in any one of eight different angular positions (see Fig. 7).

25 Extending radially outward from annular portion 39 (and preferably radially aligned with one of the notches 41 forming the periphery of opening 40) is a single arm 42 whose outer end is bent vertically upward and shaped to outwardly convexed form, as indicated at 43, for cooperation with the stationary contact or contacts of the switch.

30 Said annular portion 39 is provided with an upstanding peripheral flange 44 of substantially uniform height; said flange extending from points adjacent opposite sides of arm 42 throughout the remainder of the periphery of portion 39; the spaced ends of said flange being rounded or convexly curved downwardly, as indicated at 45 and 46 in Fig. 8, to avoid sharp corners at the upper edges thereof respectively.

35 The flat upper edge of flange 35 is adapted to be continuously engaged throughout substantially its entire length (as shown in Fig. 3) by a collector ring 47 formed integrally with an arm 48 bent downwardly at a predetermined angle from a substantially vertical portion 49 which is bent to extend at slightly more than a right angle to the portion 50, which is in turn bent at substantially a right angle to portion 51. Portion 51 is provided with a circular opening (not shown) to accommodate the reduced end of a machined hollow metal terminal member 52; said reduced end being upset over the inner surface of portion 51; as shown at 53 in Fig. 7, to rigidly and permanently secure said parts to each other. Member 52 is provided with an intermediate cylindrical

portion 54 which fits into one of the eight equally spaced notches or grooves of like shape formed in the peripheral wall of base 25, as hereinafter described. Member 52 is also provided with a relatively large outer end portion 55 of square contour which non-rotatably fits into an upwardly opening notch portion in said base. Member 52 is tapped, as indicated at 56 in Fig. 8, to receive the shank of a binding screw 57 (see Fig. 7).

In an eight-position, single-break switch of the character illustrated in Figs. 1 to 9 a total of eight terminal members 52 will be employed; seven of such members having rigidly and permanently attached thereto like resilient stationary contact elements of the form best illustrated at 58 in Fig. 8. Thus each element 58 is provided with a flat perforated portion 59 over which the reduced end 53 of member 52 is upset as shown; a relatively longer straight portion 60 which is bent in a counterclockwise direction at an angle of approximately thirty-one degrees with respect thereto, said portion 60 preferably having a downwardly opening notch 61 formed therein to increase the resiliency thereof. At the right-hand end of portion 60 of each element 58 (see Fig. 8) the latter is cut away or downwardly offset, as indicated at 62, to insure adequate spacing between the stationary contact tips and the collector ring 47 when employed. Cut away portion 62 is bent in a clockwise direction with respect to portion 60, as indicated at 63, and the free end thereof is bent in a counterclockwise direction, as indicated at 64. The forward upper edge of said end is preferably curved downwardly, as indicated at 65, and said end is undercut at 66, leaving a sufficient height of material to afford a proper contact tip 67 for cooperation with the aforementioned contactor tip 43.

In practice we prefer to form the element from a composite metal strip or plate; the inner surface 68, Fig. 8, of which consists of a relatively thin layer of silver and the outer surface 69 of which consists of a relatively thicker layer of bronze or hard copper.

For the purpose of accommodating the terminal members 52 and the stationary contacts or the collector ring respectively attached thereto, each base 25 is provided with eight equally spaced auxiliary recesses extending approximately tangentially from the main recess 26 to the periphery of the base (see Figs. 5 and 7). Thus the upwardly opening square portion of each peripheral notch is illustrated at 70 in Fig. 5; the same accommodating the square outer end portion 55 of a terminal member 52 to restrain the latter against rotation. The portion of each peripheral notch which accommodates the cylindrical portion 54 of each member 52 has a flat lower mid-portion or surface 71, on opposite sides of which are upwardly angled surfaces or fillets 72 and 73. A curved or concave surface to accommodate said portion 54 might, of course, be substituted for the surfaces 71, 72 and 73.

That portion of each auxiliary recess which is shaped to accommodate the reflexed portions 59 and 60 of a contact element 58 is designated by the numeral 74 (see Figs. 5 and 7); it being understood that the angular wall 75 of said portion is so arranged as to require a predetermined degree of further bending or flexing of portion 60 with respect to portion 59 to permit assembly of each combined contact and terminal member with respect to the base 25. Said wall 75 extends inwardly toward main recess 26 until the former

merges tangentially with the outer periphery of a cylindrical stud 76 (Fig. 7) formed integrally with the bottom wall of recess 26. The stud 76 and an adjacent portion of wall 75, as indicated at 77, are of substantially less height than the remainder of said wall 75, such remainder preferably being substantially flush with the upper surface of base 25. Such lower height of the wall portion 77 and stud 76 is adapted to function in conjunction with the cut away or undercut 68 of the end portion or tip 67 of the stationary contact to afford adequate clearance for the latter upon outward flexing or movement thereof as an incident to engagement therewith of the contactor tip 43. The other sides of wall portions 75 and 77 and stud 76 form complementary portions of the next adjacent auxiliary recess 74, as is readily apparent.

As shown in Fig. 5 each auxiliary recess 74 is provided just inside of notch portion 71, 72, 73 with a flat ledge or fillet 78 formed integrally with base 25, said ledge being adapted to act as a seat for the lower edge of portion 59 (Fig. 8) of a contact element 58, whereby the remainder of the length of the latter is spaced upwardly a substantial distance above the bottom wall of said auxiliary recess. By this means free flexing of the active portion of each stationary contact with respect to base 25 is provided for, as indicated in Fig. 3.

As aforeindicated all of the auxiliary recesses 74 are of identical form so that each of the same is adapted to accommodate a combined stationary contact and terminal member of the character just described. However, when a single-break switch is desired the aforescribed collector ring 47 is employed, and the terminal member 52 and portions 49, 50 and 51 are likewise adapted to fit into any one of said auxiliary recesses 74. For practical reasons, however, we prefer to position said portions of the collector ring within the auxiliary recess 74 at the right-hand side (Fig. 7) of a vertical passage 79 of circular cross section which extends through base 25. Base 25 is provided with two other passages 80 and 81; the passages 79 and 80 being spaced like distances from passage 81, which distances are greater than the distance of passages 79 and 80 from each other. By this means assembly of the insulating bases in only one rotary relationship to each other and to the metal supporting and cover plate (hereinafter described) is insured.

As will be apparent from Figs. 3 and 7, the aforementioned studs 76 jointly define a circle in close proximity to the respective carrier 33 to assist in insuring properly centered relationship of the latter to its base 25. Also as shown in these figures, the arm 42 and tip 43 of the contactor project radially into overlapping relationship to the studs 76 to afford the proper degree of outward flexing of the stationary contact arms, whereby an adequate amount of contact pressure is insured.

As best illustrated in Figs. 1 and 7, when all of the eight wiring terminal members 52 and binding screws are in assembled position upon each base 25 the periphery of the latter is rendered substantially dust-tight. However, as best illustrated in Fig. 1, the terminal members 52 extend upwardly slightly beyond the upper surface of base 25, and to peripherally seal the upper end of said base we prefer to employ a resilient insulating gasket 82 which is of sufficient width to overlie each terminal member 52 and the portion 51 of a stationary contact or the portion 51 of the

collector ring attached to the terminal member. Gasket 82 is preferably composed of finely divided cork and synthetic rubber. Such a composition is sold commercially under the trade name of "Corprene." Gasket 82 is provided with eight equally spaced inwardly extending bulges or enlargements (not shown) to accommodate a corresponding number of perforations, three of which will be aligned with the openings or passages 79, 80 and 81 in the base in any one of eight different rotary positions of the gasket with respect to the base.

When the switch includes two or more bases 25, a gasket 82 will thus be interposed between each two adjacent bases, the same serving both as dust-tighting means and as cushioning means to absorb the strain upon the bases as an incident to final attachment of the latter to each other and to the supporting means. Due to the interlocking of bases 25 with said gaskets 82 rotation of the bases 25 with respect to each other is definitely prevented. Superimposed upon the gasket 82 associated with the upper base 25 of a group is a flat punched insulating plate 83 which is substantially thicker than gasket 82 but of the same peripheral contour as the latter (see Fig. 3). Plate 83 is preferably composed of a so-called "phenolic paper base material." Plate 83 is provided with eight equally spaced circular openings to be aligned with the corresponding openings in the gasket or gaskets 82; said plate being also provided with a central circular opening 84 of substantially the same size as the opening 85 in ring 47 (Figs. 3 and 8). Openings 84 and 85 are adapted to freely accommodate a hollow insulating bushing 86 consisting of a suitable length of "Bakelite" tubing; said bushing performing the same function as the downward projection of a base 25 with respect to a switch positioned therebelow; namely, to retain the contactor 38 against substantial upward displacement from its carrier 33.

Superimposed upon insulating plate 83 is a flat, punched sheet metal stop plate of the form best illustrated at 87 in Fig. 9; plate 87 having three openings 88, 89 and 90 adapted to be respectively aligned with the passages 79, 80 and 81 in the base or bases 25. Plate 87 is provided with a relatively large substantially circular central opening 91 having a single inwardly projecting stop lug 92 which is radially aligned with the aforementioned opening 80. The opposite side edges of lug 92 are selectively engageable by opposite side edges of a single stop lug 93 formed upon a cooperating flat, punched sheet metal stop plate 94. The lower surface of plate 94 is adapted to bear upon the upper surface of plate 83 (see Fig. 3). Stop plate 94 is formed of slightly thinner metal than plate 87, but the arrangement is such that the lower surfaces thereof are normally in coplanar relationship to each other. Plate 94 is provided with a centrally located square opening 95 adapted to slidably accommodate the aforementioned square portion 29 of the operating shaft of the switch; whereby plate 94 is constrained to rotate with said shaft. Plate 94 is biased downwardly, as shown in Figs. 3 and 9, by a spring plate 96 formed of bronze or a similar resilient metal; plate 96 being bent or bowed upwardly between opposite ends 97 and 98 thereof, and the same having a square opening 99 therein to likewise accommodate said square portion 29 of the shaft. Said portion 29 is provided with a transverse passage to accommodate a pin 100, the intermediate portion of which is pref-

erably provided with an enlargement (not shown) to afford a drive fit thereof within said shaft opening; the spring 96 being placed under the desired degree of compression against plate 94 as an incident to assembly of the switch parts.

Also as shown in Fig. 3 the pin 100 affords at its upper surface an abutment for the lower surface of the approximately rectangular intermediate or central portion 101 of a metal member, preferably composed of a punched plate of spring steel of the form best illustrated in Fig. 4. Thus member 101 is provided with an opening 102 to accommodate shaft portion 29, whereby said member is constrained to rotate with the shaft. Said portion 101 is integrally connected, by neck portions 103 and 104, with a ring 105, the ring sections 106 and 107 at opposite sides of necks 103 and 104 being bent upwardly to a predetermined degree (see Fig. 3); each section 106 and 107 having an opening 108 and 109 respectively formed therein to accommodate portions of a pair of metal balls or spheres 110 and 111, whereby said balls are biased upwardly into engagement with the inner surface 112 of a metal cover member 113.

Said under surface 112 of cover member 113 is provided with a circular series of eight equally spaced recesses 114 to 121, respectively, of approximately hemispherical form; said recesses 30 being formed by embossing or deforming the material of said cover member, as best illustrated in Figs. 2 and 3. Cover member 113 is provided with a flange 122 overlying the stop plate 87, and said flange is provided with three 35 properly positioned openings to accommodate the threaded shanks of bolts 123 which project upwardly through the various other parts of the switch. The kerfed heads of said bolts are designated by the numeral 124 (Figs. 1 and 3), and 40 nuts 125 are provided for securing or clamping the parts in assembled relation.

As will be apparent the balls 108 and 109 are adapted to cooperate with diametrically opposed pairs of the recesses 114 to 121 to definitely and accurately locate shaft 29 and contactor 38 in any one of eight operative positions; the camming action of said balls with respect to said recesses serving to normally insure movement of the contactor from each operative position to another with a quick action.

Cover member 113 is provided with a central circular opening 126 (Fig. 3) which is adapted to accommodate the reduced lower end 127 of an externally threaded hollow metal bushing 128; said bushing having an external slot 129 formed therein, and cover member 113 having a partially sheared and upwardly bent lug or projection 130 formed thereon which fits into slot 129 (Fig. 3) to insure assembly and maintenance of the bushing and cover member at only one rotary angle relatively to each other. This arrangement thus also insures positioning and maintenance of slot 129 at a predetermined rotary angle with respect to said cover member, for proper positioning of the switch unit with respect to an indicating dial or plate with which the operating knob is adapted to cooperate. As shown in Fig. 1, a panel or supporting plate 131 may have suitable numerals or legends (not shown) applied to the outer surface thereof; said panel having an opening 132 formed therein to accommodate bushing 128. A sheet metal member 133 of substantially washer form fits over said bushing and has an inwardly extending tongue (not shown) to fit between the side

walls of the aforementioned slot 129 (Fig. 3). Member 133 has an integral lug 134 bent downwardly at substantially a right angle thereto, and panel 131 is provided with an opening 135 into which said lug fits to prevent rotation of member 133 relatively to the panel.

As shown in Figs. 1 and 3, bushing 128 is provided with an upwardly facing shoulder 136 which is adapted to seat against the lower surface of the panel 131 or other suitable support. A hexagonal nut 137 cooperates with the thread on bushing 128 to clamp the assembled switch in position; a split or other type of lock-washer 138 preferably being interposed between nut 137 and member 133.

The cylindrical portion 139 of the shaft is adapted to rotatably bear within the bushing 128 as best illustrated in Fig. 3; said shaft having an annular kerf 140 therein into which a split washer 141 is forcibly insertable, said washer overlying the flat upper end of bushing 128 to positively limit the downward displacement of the shaft under the bias of spring member 101. The extreme upper end portion 142 of the shaft is cut away to provide a flat side 143; said flat side as shown being preferably located in a plane at right angles to the direction in which the pointed portion 144 of knob 145 extends. As best illustrated in Fig. 20, knob 145 is preferably of substantially wedge shape in horizontal cross section; the same having a relatively large downwardly opening cylindrical recess, shown in dotted lines at 146 in Fig. 1, to accommodate the upper end of bushing 128, and a relatively smaller cylindrical recess 147 to accommodate the flatted upper end portion 142 of the shaft. Knob 145 is provided at its rear end with a passage 148 leading to recess 147, said passage having a tapped portion 149 to accommodate a set screw 150 whose inner end engages the flat surface 143 to secure the knob and shaft against movement relatively to each other.

In practice knob 145 is also preferably provided at one side thereof with a second tapped passage 151 to accommodate an additional set screw 152 whose inner end frictionally engages the cylindrical surface of the shaft to further assist in restraining the knob against movement relatively to the shaft. Knob 145 is preferably of the special form illustrated in Figs. 1 and 20, although a knob of any desired form might, of course, be employed.

Although we have thus far described a switch having seven "on" positions and one "off" position with a contactor of the single-pole type, it is to be understood that the number of "on" positions might be decreased and the number of "off" positions correspondingly increased by merely omitting the stationary contacts at one or more points in the respective bases 25. By this means a very large variety of different circuit controlling arrangements may be provided. When any of the combined stationary contact and terminal members are omitted, we prefer to insert in the recess for each terminal portion a closure member or plug formed of rubber or similar elastic material, as shown at 153 in Fig. 10.

Similarly when it is desired to provide a single circuit connection for a plurality of vertically aligned terminals a bus member or connector of the form illustrated at 154 in Fig. 6 may be employed. Connector 154 is shown as provided with three circular openings 155 properly spaced to accommodate the shanks of three of the binding screws 51, only one of which would then be re-

quired for clamping of the bared end of a common circuit wire. Connector 154 is also preferably provided with rectangular openings 156 which produce opposed relatively narrow strip portions 157 to facilitate bending of the connector over the outwardly projecting peripheral portions of all but the lowermost base. The number of connectors employed may, of course, be varied in accordance with the requirements of a given installation. Similarly the connectors may be made in various lengths for cooperation with the terminal portions of from two to any desired number of bases.

After tightening of nuts 125 the exposed ends 15 of the bolt shanks 123 are preferably upset there-over to positively prevent accidental loosening of said nuts. If desired, of course, rivets (not shown) of suitable length might be substituted for bolts 123 and nuts 125.

Also while we have described a stationary stop plate 87 having a single stop lug 92 formed integrally therewith, we have illustrated in Fig. 15 a method of punching or forming said stop plate so that any one or more of the additional stop lugs 158, 159 and 160 may be provided. Thus with the lug 93 of movable stop plate 94 positioned as illustrated the switch would be limited to movement to four different operative positions by co-operation of lug 93 with the properly spaced stationary stop lugs 92 and 158. If the punch parts (not shown) are co-ordinated to provide for removal of lug 158 while permitting lugs 92 and 159 to remain intact the lug 93 might then be moved in a clockwise direction to provide a five-position switch. In like manner, if lugs 158 and 159 are removed, while permitting lugs 92 and 160 to remain intact, the lug 93 might then be moved clockwise from the position illustrated to provide a switch of the six-position type. By merely turning stop plate 87 of Fig. 15 upside down, so that with lug 93 in the position thereof illustrated it would be located between lugs 92 and 160, a switch of the two-position type would be provided. With plate 87 so turned upside down, and with lug 160 removed, so that lug 93 may be moved clockwise between lugs 92 and 159, a switch of the three-position type would be provided. It will be noted that the aforementioned modifications may be effected without requiring any 50 change or rearrangement of the other parts of the switch. If a seven-position switch were desired, the same could be provided by removing the lug 92 and one or the other of the lugs 158 or 160; such an arrangement, however, requiring a 55 different rotary positioning of the contactor with respect to its carrier 33.

As a further modification of the switch hereinabove described a double-pole, or double-break, contactor of the character shown at 161 in Fig. 13 or at 162 in Fig. 17 may be substituted for the single-break contactor 38 aforementioned. The contactor 161 is of a special form, the same consisting of a flat punching composed of copper or the like, the same having a substantially circular main portion, a pair of diametrically opposed radial lugs 164 and 165 forming contactor tips, and a pair of radial lugs 166 and 167 located on opposite sides of lug 165, with their respective radial center lines spaced forty-five degrees from the latter. Contactor 161 is provided with a substantially square central opening 168 to provide for positioning thereof within carrier 33 (Fig. 8) in any one of four different angular relations. A contactor 161 is employed in the four-position switch of Fig. 11, from which it will be noted that

a special arrangement of only four stationary contact members 169 is required. Thus with contactor 161 in its "off" position, as shown in Fig. 11, upon clockwise rotation thereof through an angle of forty-five degrees the single contactor tip 164 will engage the first of the group of three stationary contacts and the contactor tip 166 will engage the single stationary contact. In the next position the contactor tip 165 will engage said single stationary contact and the single tip 164 will engage the second stationary contact of said group; whereas in the third "on" position contactor tip 167 will engage the single stationary contact and the contactor tip 164 will engage the third stationary contact of said group. Ordinarily the stationary and movable stop plates of the switch will be formed and arranged to prevent any further clockwise movement of contactor 161, but it will be obvious that, if desired, the same might be permitted to move through another forty-five degree angle, to provide an "off" position at each end of the angular throw of the contactor, with three "on" positions therebetween. As will be understood, the switch of Fig. 11 provides for sequential control of three different electrical circuits.

As an alternative, a contactor substantially like that shown at 161, but with the tips 166 and 167 omitted or removed, might be employed; in which event a stationary contact 169 would be positioned on each side of the single contact shown in Fig. 11, so that the remaining contactor tips 164 and 165 would jointly engage sequentially different pairs of the respective groups of three stationary contacts. Other modifications will at once suggest themselves to those skilled in the art.

The contactor 162 of Fig. 17 is functionally like the contactor 161 of Fig. 11, but differs from the latter in respect of having a form of opening 170 (like the opening 40 of contactor 38, Fig. 8) whereby contactor 162 may be located in any one of eight different angular positions with respect to carrier 33. The radial lugs 171 to 174, inclusive, of contactor 162 have their respective tips 175 to 178, inclusive, bent upwardly and to outwardly convexed form in horizontal cross section to afford a relatively large area of engagement with the stationary contacts of the switch.

When it is desired to provide for bottom wiring of a switch employing a single base 25 having wiring terminal screws, or for the lower base 25 of a multi-pole switch like that shown in Figs. 1 and 3, we prefer to attach to the lower surface of the base (or lowermost base) 25 by means of bolts substantially like the bolts 123 aforescribed, and of suitable length a punched insulating plate of the form illustrated at 179 in Fig. 19. Plate 179 has a central circular opening 180 to fit around the downward extension 30 of base 25, and three openings or passages 181, 182 and 183 to be respectively aligned with the passages 79, 80 and 81 (Fig. 7) in base 25, whereby the bolt heads will underlie plate 179 to retain the same in assembled position. Plate 179 is provided with eight equally spaced peripheral notches 184 which are respectively vertically aligned with the eight terminal recesses in the base; said notches each being adapted to accommodate, with a fairly close fit, the inwardly angled arm 185 (Fig. 18) of a terminal extension member 186, the vertical upper end portion 187 of which is provided with an opening 188 to provide clearance for the shank of a terminal screw 157 of the switch; said portion 185 having near its lower end a tapped opening

189 to accommodate an additional screw like the screws 157. The side walls of notches 184 thus serve to maintain extensions 186 in properly spaced relationship to each other.

5 In the solder-lug terminal type of switch shown in Figs. 11 to 15, inclusive, certain of the parts may be identical with the corresponding parts aforescribed, and have been given like numerals of reference. In this modified form of switch, however, the one-piece molded insulating base 180 may be shallower, or of considerably less depth, than the base 25 aforescribed. Such shallowness is possible primarily because of the relatively small height of the one-piece combined contact and terminal members 181, as compared with the combined contact and terminal members 52, 58 aforescribed. Thus, upon comparison of Fig. 11 with Fig. 7, it will be noted that the main and auxiliary recesses in the two bases are quite similar in shape or contour; the difference in height of the base recesses corresponding substantially to the height of the upward extension 31 in base 25 (see Fig. 3). Thus, as best illustrated in Fig. 12, the aforescribed molded insulating carrier 33 is adapted to rotatably seat directly against the bottom wall 192 of main recess 193; the major portion 194 of each auxiliary recess having its bottom wall in a corresponding plane. As shown at 195 in Figs. 11 and 30 12, however, the outer portion of each auxiliary recess is upon a slightly higher plane, whereby the flexible stationary contact portion of each member 191 is located a substantial distance above the bottom walls of said main and auxiliary recesses, as indicated at 196.

35 The blank from which each combined contact and terminal member is produced is illustrated in Fig. 14, the points or lines of bending thereof being shown in dotted lines at 197, 198, 199 and 200. Each member 191 is provided in the lower edge of portion 201 thereof with a notch 202 for cooperative engagement with rectangular stud 203 formed integrally with the bottom wall portion 195 of each auxiliary recess. The portion 204 of each member is provided in its lower edge with a rectangular notch 205 which serves primarily to increase the flexibility of the contact portion. The upper edge of the free end portion of each member 191 is preferably cut away, as indicated at 208 in Fig. 14, to afford electrical clearance between the same and a collector ring when employed. The lower edge of the extreme end of the contact portion is also preferably cut away, as indicated at 209 in Fig. 14, to afford clearance between the same and a stud 206 and wall portion 207, as shown in Fig. 11.

40 A flat punched insulating member 211 of washer form is adapted to overlie contactor 161; said member also underlying the aforescribed insulating plate 83, whereby substantial upward displacement of said contactor is prevented. Member 211 is provided with a circular central opening 212 to provide rotary clearance for the portion 29 of the operating shaft. A gasket 82 of the character aforescribed directly overlies the peripheral portion of each base 190, including portions of the members 191 to retain the said members in proper position and to insulate the same. The other elements of the switch, including the operating knob may be of the form heretofore described.

45 As aforeindicated a stationary stop plate 87 having stop lugs 82 and 158 for cooperation with the lug 93 of the movable stop plate, as shown

in Fig. 15, are required for a four-position switch like that of Figs. 11 and 12.

In some installations it is desirable to provide a switch requiring an angular movement of the contactor through ninety degrees from each operative position thereof to another. Such operation is afforded by providing a metal cover member 213 having only four equally spaced recesses 214 to 217, inclusive, formed in the lower surface thereof, as indicated in Fig. 16; member 213 being otherwise identical with the cover member 113 aforescribed.

It is to be understood that the term "multipole" employed herein refers to a switch of the present character embodying two or more insulating bases, each of which has switch parts associated therewith to provide for control of one or more electric circuits, whether circuits related to the respective bases are completed or interrupted in a given rotary position of the operating shaft.

With reference to switches of the solder-lug type, as shown in Figs. 11 and 12, it is to be understood that a single-break contactor of the form shown at 38 in Fig. 8 might be employed; a collector ring substantially like that shown at 47 in Fig. 8 being employed, except that a reflexed portion and perforated solder lug portion like those of members 491 would be formed integrally therewith.

The one-piece combined contact and terminal members of the solder-lug type are also preferably formed of composite sheet metal having an inner, or contactor-engaging, layer of silver at the contact tip and an outer layer of bronze. Also in practice the completely formed contact and terminal members of this type are preferably provided with a thin plating of silver to insure a good soldered electrical connection of circuit wires to the terminal portions, and to improve the appearance thereof.

Although we have specifically described certain preferred embodiments of my invention, it will be apparent to those skilled in the art that various alternative combinations of elements may be provided without departing from the spirit of my invention or the scope of the appended claims.

As best illustrated in Fig. 8, the bottom wall 218 of the upwardly opening recess in carrier 33 is formed to provide a relatively shallow depression or sub-recess 219 (see Fig. 3), whereby the electrical insulating distance between portion 29 of the shaft and contactor 38 is substantially increased.

We claim:

1. In a rotary electric switch, in combination, a molded insulating carrier member having a recess formed in one face thereof, said member having an axial opening therethrough, a metal contactor having a portion freely insertable into said recess and retained by the walls of the latter in spaced relation to said axial opening, said member having a multiplicity of spaced grooves extending from said recess to the periphery of the former and said contactor having at least one lug formed integrally therewith and extending through any one of a number of said grooves a substantial distance beyond the periphery of said member.

2. In a rotary electric switch, in combination, a molded insulating carrier member having a recess formed in one face thereof, said member having an axial opening therethrough, said member having an integral flange upstanding from the bottom wall of said recess, the inner periph-

ery of said flange being aligned with said opening, a sheet metal contactor having a portion freely insertable into said recess and adapted to surround said flange to be insulated by the latter from an operating shaft positioned within said opening, said member having a multiplicity of spaced grooves extending from said recess to the periphery of the former, and said contactor having a lug formed integrally therewith and extending through any one of a number of said grooves a substantial distance beyond the periphery of said member for cooperation with a stationary contact of suitable form.

3. In a multi-position rotary electric switch, in combination, a molded insulating carrier member having a recess formed in one face thereof, said member having a central opening therethrough, a sheet metal contactor having a portion freely insertable into said recess and retained by the peripheral wall of the latter in spaced and centered relation to said opening, said member having a multiplicity of spaced grooves extending through the wall of said recess throughout the periphery of said member, said contactor having at least one lug formed integrally therewith and extending through any one of a number of said grooves a substantial distance beyond the periphery of said member, and the end portion of said lug being bent to extend upwardly a substantial distance therefrom, said upwardly bent end portion being of arcuate form in horizontal cross section.

4. In a multi-position rotary electric switch, in combination, a molded insulating carrier member, said member having a flat lower surface and an upstanding peripheral wall defining a recess in the upper surface thereof, said wall having a multiplicity of equally spaced grooves formed therein and leading from said recess, a relatively large central opening formed in said member, the walls of said opening being in planes at right angles to certain of said notches, an upstanding flange formed integrally with the bottom wall of said recess and having its inner periphery coplanar with the respective walls of said opening, a sheet metal contactor having a flat portion freely insertable into said recess, said contactor having an opening therein to accommodate said flange, and said contactor having an integral lug adapted to extend through any one of a multiplicity of said grooves a substantial distance beyond the periphery of said member for cooperation with a resilient stationary contact of suitable form.

5. In a multi-position rotary electric switch, in combination, a molded insulating carrier member of circular contour, said member having a flat lower surface and an upstanding peripheral wall, said member having a centrally located opening and an integral upstanding flange closely surrounding said opening, said peripheral wall and said flange defining a recess, a sheet metal contactor having a flat portion freely insertable into said recess, said contactor having at least one laterally extending lug formed integrally therewith, said peripheral wall having a multiplicity of equally spaced radial grooves formed therein, any one of a number of said grooves being adapted to accommodate said lug, whereby the latter is adapted to cooperate with an associated resilient stationary contact of suitable form, and means comprising a shaft penetrating said opening in said member and engaging the walls thereof to provide for rotation of the latter in either direction selectively.

6. In a rotary electric switch, in combination, a molded insulating carrier member having a substantially circular recess therein, said member having a centrally located opening of polygonal form in transverse cross section, a metal member having a portion of substantially annular form freely insertable into said recess and retained by the walls of the latter in spaced relation to said opening, said insulating member having a multiplicity of equally spaced radial grooves extending from the periphery thereof to said recess, said metal member having a lug formed integrally therewith and extending through any one of said grooves a substantial distance beyond the periphery of said insulating member to act as a contactor, said annular portion of said metal member having a flange upstanding from the periphery thereof from points adjacent opposite sides of said lug, said flange being adapted for continuous engagement by a resilient ring-shaped metal clip to be connected to a source of current supply, and said contactor lug being adapted for movement in either direction into and out of engagement with one or more resilient stationary contacts of suitable form.

7. In a rotary electric switch, in combination, a molded insulating carrier member having a recess therein, said member having a centrally located opening of polygonal form in transverse cross section, a sheet metal member having a portion of substantially annular form freely insertable into said recess and retained by the walls of the latter in spaced relation to said opening, said insulating member having a multiplicity of equally spaced radial grooves extending from the periphery thereof to said recess, said metal member having a lug formed integrally therewith and extending through any one of said grooves a substantial distance beyond the periphery of said insulating member to act as a contactor, said annular portion of said metal member having a flange upstanding from the periphery thereof from points adjacent opposite sides of said lug, said flange being adapted for continuous engagement by a resilient ring-shaped metal clip to be connected to a source of current supply, said contactor lug being adapted for movement in either direction into and out of engagement with one or more resilient stationary contacts of suitable form, an upstanding flange formed integrally with the bottom wall of said recess and having its inner periphery alined with said opening, said annular portion of said metal member being adapted to accommodate said last mentioned flange in spaced relationship thereto.

8. In a rotary electric switch, in combination, a molded insulating carrier member, said member having a recess formed therein, said member having a centrally located relatively large opening of square form therein, a flat sheet metal member having a portion of substantially annular form freely insertable into said recess and retained by the latter in spaced relation to said opening, said insulating member having a multiplicity of equally spaced radial grooves formed in the peripheral wall of said recess, said metal member having at least two diametrically opposed lugs formed integrally therewith and respectively extending outwardly through any one of a number of diametrically opposed pairs of said grooves, whereby said lugs may be moved jointly into and out of bridging engagement with a diametrically opposed pair of resilient stationary contacts, an integral flange upstanding from the bottom wall of said recess and having its inner surfaces alined

with the walls of said opening, and said annular portion of said metal member having its inner periphery shaped to accommodate said flange in any one of at least four positions.

9. In a multi-position rotary electric switch, in combination, a molded insulating base, said base having a centrally located main recess, an auxiliary recess formed in the bottom wall of said first mentioned recess, said base having a boss formed upon the lower surface thereof to form the lower portion of said auxiliary recess, the bottom wall of the latter being made relatively thin to provide for removal thereof by broaching, if desired, an insulating carrier member, said member having a flat lower surface adapted to seat within said recess, said member having a recess formed in the upper surface thereof and a multiplicity of spaced notches extending radially through the peripheral wall of said recess therein, a metal member positioned within said last mentioned recess and having at least one integral lug projecting laterally through any one of a number of said notches, said insulating base having a multiplicity of spaced auxiliary recesses extending from the periphery of said main recess and opening to the periphery of said base, and a plurality of combined resilient stationary contact and terminal members positioned within certain of said auxiliary recesses, the resilient contact portion of at least one of said members being so positioned as to provide for movement of said lug into and out of engagement therewith selectively.

10. In a multi-position rotary electric switch, in combination, a molded insulating base, said base having a centrally located main recess, an auxiliary recess formed in the bottom wall of said first mentioned recess, said base having a boss formed upon the lower surface thereof to form the lower portion of said auxiliary recess, the bottom wall of the latter being made relatively thin to provide for removal thereof by broaching, if desired, an insulating carrier member, said member having a flat lower surface adapted to seat within said recess, said member having a recess formed in the upper surface thereof and a multiplicity of spaced notches extending radially through the peripheral wall of said recess therein, a metal member positioned within said last mentioned recess and having at least one integral lug projecting laterally through one of said notches, said insulating base having a multiplicity of spaced auxiliary recesses extending from the periphery of said main recess and opening to the periphery of said base, a plurality of resilient stationary contact and terminal members positioned within certain of said auxiliary recesses, the resilient contact portion of at least one of said members being so positioned as to provide for movement of said lug into and out of engagement therewith selectively, and the resilient contact portion of another of said members being adapted to overlie and continuously engage the metal member within the carrier recess to provide a source of current supply for said lug.

11. In a multi-position rotary electric switch, in combination, a recessed molded insulating base, an auxiliary recess formed in the bottom wall of said base, said base having a boss formed upon the lower surface thereof to form the lower portion of said auxiliary recess, an insulating member, said member having a flat surface to seat within said recess, said member having a recess formed therein and a multiplicity of spaced notches extending through the peripheral wall of said recess, a metal member positioned within

said last mentioned recess and having at least one integral lug projecting through one of said notches, said base having a multiplicity of spaced auxiliary recesses extending from the periphery of the main recess therein and opening to the periphery of said base, a plurality of resilient stationary contact and terminal members positioned within certain of said auxiliary recesses, the resilient contact portion of at least one of said members being so positioned as to provide for movement of said lug into and out of engagement therewith selectively, the resilient contact portion of another of said members being adapted to overlie and continuously engage the metal member within the carrier recess to provide a source of current supply for said lug, an insulating gasket overlying the upper surface of said base, a relatively rigid insulating plate overlying said gasket, a stationary stop plate and a movable stop plate each formed of flat sheet metal, a cover member overlying all of said parts and rigidly attached to said base, a hollow metal bushing rigidly attached to said cover member, and a rotatable shaft adapted to bear within said bushing, said movable stop plate having non-rotatable engagement with said shaft whereby rotary movement of the latter in each direction is positively limited by said stationary stop plate.

12. In a rotary electric switch, in combination, a plurality of molded insulating bases of like form, each base having a central main recess formed in the upper surface thereof, an annular ledge formed integrally with the bottom wall of said recess and providing a flat bearing surface, each base also having an extension formed integrally with the lower surface thereof, said extension having at its lower end a relatively thin integral wall which may be readily removed by broaching, said ledge and said extension thus forming part of an auxiliary recess, an insulating carrier member, said member being freely insertable into said main recess and having a flat surface adapted to seat against said ledge, said carrier member having an opening of polygonal contour formed therein and an integral flange of uniform width surrounding said opening, said member having eight equally spaced upstanding studs formed integrally therewith at the periphery thereof, whereby eight equally spaced radial grooves are provided therebetween, a metal member having a centrally perforated flat portion freely insertable between said studs and said flange, said metal member having at least one lug formed integrally therewith and extending laterally through one of said grooves to provide a contactor tip, said base having eight equally spaced auxiliary recesses formed in the upper surface thereof and extending from said main recess to the periphery of said base, a resilient stationary contact and terminal member insertable into interlocking engagement with the walls of one of said auxiliary recesses, the resilient contact tip portion of said last mentioned member being biased to a point closely adjacent the periphery of said carrier member, the contactor tip associated with the latter being movable thereby in either direction into and out of engagement with said contact tip, means comprising a second resilient stationary contact and terminal member positioned within another of said auxiliary recesses and having a portion engageable with said metal member to provide for completion of a circuit to be controlled by the latter, means for rigidly connecting said bases in superimposed relationship to each other, all

but the lowermost base having its aforementioned extension wall removed by broaching, and a shaft having a lower portion of polygonal cross section penetrating the openings in all of said carrier members to provide for rotation of the latter jointly in opposite directions selectively.

13. In a rotary electric switch, in combination, a plurality of molded insulating bases of like form, each base having a central main recess formed in the upper surface thereof, each base having an annular extension formed integrally with the lower surface thereof, said extension having at its lower end a relatively thin integral wall which may be readily removed by broaching, said extension forming part of an auxiliary recess, an insulating carrier member, said member being freely insertable into said main recess and having a flat lower surface, said carrier member having a central opening of square contour formed therein and an upstanding integral flange of uniform width surrounding said opening, said member having eight equally spaced upstanding studs formed integrally therewith at the periphery thereof, whereby eight equally spaced radial grooves are provided therebetween, a metal member having a centrally perforated flat portion freely insertable between said studs and said flange, said metal member having at least one lug formed integrally therewith and extending laterally through any one of said grooves to provide a contactor tip, said base having eight equally spaced auxiliary recesses formed in the upper surface thereof and extending from said main recess to the periphery of said base, a resilient stationary contact and terminal member insertable into interlocking engagement with the walls of one of said auxiliary recesses, the resilient contact tip portion of said last mentioned member being biased to a point closely adjacent the periphery of said carrier member, the contactor tip associated with the latter being movable thereby in either direction into and out of engagement with said contact tip, means comprising a second resilient stationary contact and terminal member positioned within another of said auxiliary recesses and having a portion engageable with said metal member to provide for completion of a circuit to be controlled by the latter, means for rigidly connecting said bases in superimposed relationship to each other, all but the lowermost base having its aforementioned extension wall removed by broaching, a shaft having a lower portion of square cross section penetrating the openings in all of said carrier members to provide for rotation of the latter jointly in opposite directions selectively, a cover member superimposed upon the upper base of the group and rigidly secured thereto, an externally threaded metal bushing rigidly secured to said cover member, said bushing having a passage of circular cross section extending therethrough, said shaft having a cylindrical portion adapted to bear within said passage, and means associated with said shaft above and below said bushing to restrain said shaft against substantial endwise displacement.

14. In an electric switch, in combination, a plurality of insulating bases produced in like form, each base having a central main recess formed in the upper surface thereof, a ledge formed integrally with the bottom wall of said recess and providing a flat bearing surface, each base also having an extension formed integrally with the lower surface thereof, said extension having at its lower end a relatively thin integral

wall which may be readily removed by broaching, said ledge and said extension thus forming part of an auxiliary recess, an insulating carrier member, said member being freely insertable into said main recess and having a flat lower surface adapted to seat against said ledge, said carrier member having a central opening formed therein and an upstanding integral flange surrounding said opening, said member having spaced upstanding studs formed integrally therewith at the periphery thereof, whereby spaced radial grooves are provided therebetween, a sheet metal member having a portion freely insertable between said studs and said flange, said metal member having at least one lug formed integrally therewith and extending through any one of a number of said grooves to provide a contactor tip, said base having spaced auxiliary recesses formed in the upper surface thereof and extending from said main recess to the periphery of said base, a resilient stationary contact insertable into one of said auxiliary recesses, the contactor tip associated with the carrier member being movable thereby in either direction into and out of engagement with said contact tip, means comprising a second resilient stationary contact positioned within another of said auxiliary recesses and having a portion engageable with said metal member to provide for completion of a circuit to be controlled by the latter, means for rigidly connecting said bases in superimposed relationship to each other, all but the lowermost base having its aforementioned extension wall removed by broaching, a shaft penetrating the openings in all of said carrier members to provide for rotation of the latter jointly in opposite directions selectively, a cover member superimposed upon the upper base of the group and rigidly secured thereto, an externally threaded bushing rigidly secured to said cover member, said bushing having a passage extending therethrough, said shaft being accommodated within said passage, said shaft having means projecting laterally therefrom below said bushing, a resilient metal member of convexed form adapted to seat against said projecting means, an opening formed in said last mentioned member, a metal ball adapted to bear within said opening and pressed by said member against the lower surface of said cover member, said shaft having associated means overlying the upper end of said bushing to positively limit downward displacement of said shaft.

15. In an electric switch adapted for rotation in either direction selectively to any one or more of eight operative positions, in combination, an insulating base of relatively small depth, said base having a main recess and eight equally spaced peripheral recesses communicating therewith, an insulating carrier member rotatably supported within said main recess, said member having a central opening formed therein and eight equally spaced upstanding studs formed integrally therewith at the periphery thereof whereby a corresponding number of radial grooves are provided therebetween, a sheet metal member having a flat portion freely insertable within the area defined by said studs, said flat portion having a central opening of substantially greater size than said carrier opening, said flat portion having a lug formed integrally therewith and extending radially therefrom through one of said grooves to a point beyond the periphery of said carrier member, a plurality of resilient stationary contact and wiring terminal members

each having an interlocking fit within one of said peripheral recesses, the wiring terminal portions of said members being exposed at the outer peripheral surface of said base, said lug being movable in either direction selectively into or out of engagement with the resilient contact portion of at least one of said members, the resilient contact portion of at least one other of said members being adapted to simultaneously engage another portion of said sheet metal member to provide for completion of a circuit controlled thereby, a metal cover member overlying the upper surface of said base and rigidly attached to the latter in insulated relation to said switch parts, and a shaft supported by said cover member and having a portion non-rotatably engaged with the walls of said carrier opening.

16. In an electric switch adapted for rotation in each direction selectively to any one or more of eight operative positions, in combination, a molded insulating base of relatively small depth, said base having a centrally located main recess and a multiplicity of peripheral recesses communicating therewith, a molded insulating carrier member rotatably supported within said main recess, said member having a non-circular central opening formed therein and a multiplicity of upstanding studs formed integrally therewith at the periphery thereof whereby a corresponding number of radial grooves are provided therebetween, a metal member having a flat portion freely insertable within the area defined by said studs, said flat portion having a central opening of substantially greater size than said non-circular opening, said flat portion having at least one lug formed integrally therewith and extending radially therefrom through a corresponding number of said grooves a substantial distance beyond the periphery of said carrier member, a plurality of resilient stationary contact and wiring terminal members each having an interlocking fit within one of said peripheral recesses, said carrier member being movable in either direction selectively from any one of a multiplicity of different rotary positions to effect sequential completion and interruption of a plurality of alternative circuits, a cover member overlying the upper surface of said base and rigidly attached to the latter, a shaft rotatably supported by said cover member and having a portion non-rotatably engaged with the walls of said non-circular opening, a perforated flat metal stop plate interposed between said cover member and said base for fixed support with respect thereto, a second flat metal stop plate interlocked with said shaft for rotation thereby, said stop plates being arranged in coplanar relationship to each other, said movable stop plate having a single lug formed thereon, and said fixed stop plate having at least one lug formed thereon for cooperative engagement by said single lug to positively limit the degree of rotation of said shaft in each direction respectively.

17. In an electric switch adapted for rotation in either direction to any of eight operative positions, in combination, an insulating base of relatively small depth, said base having a centrally located main recess and eight equally spaced peripheral recesses communicating therewith, an insulating carrier member rotatably supported within said main recess, said member having a non-circular central opening formed therein and eight equally spaced upstanding studs formed integrally therewith at the periphery thereof whereby a corresponding number of radial

grooves are provided therebetween, a sheet metal member having a flat portion freely insertable within the area defined by said studs, said flat portion having a central opening of substantially greater size than said non-circular opening, said flat portion having at least one lug formed integrally therewith and extending radially therefrom through a corresponding number of said grooves a substantial distance beyond the periphery of said carrier member, a plurality of resilient stationary contact and wiring terminal members each having an interlocking fit within one of said peripheral recesses, said carrier member being movable to any one of a multiplicity of different rotary positions to effect sequential completion and interruption of a plurality of alternative circuits, a metal cover member overlying the upper surface of said base and rigidly attached to the latter, a shaft rotatably supported by said cover member and having a portion non-rotatably engaged with the walls of said non-circular opening, a perforated, flat sheet metal stop plate interposed between said cover member and said base for fixed support with respect thereto, a second flat sheet metal stop plate interlocked with said shaft for rotation thereby, said movable stop plate having a single lug formed thereon, said fixed stop plate having at least one lug formed thereon for cooperative engagement by said single lug to positively limit the degree of rotation of said shaft in each direction respectively, the rotatable support for said shaft comprising an externally threaded hollow metal bushing rigidly attached to said cover member, said shaft having a kerf formed in the periphery thereof, an open-sided metal washer forcibly engaging said shaft within said kerf, said washer overlying the upper end of said bushing to positively limit the downward displacement of said shaft, a resilient metal indexing member of substantially circular contour underlying the central portion of said cover member, said indexing member having a central opening the walls of which non-rotatably engage a portion of said shaft for rotation by the latter, diametrically opposite side portions of said indexing member being bent upwardly toward said cover member and each having a relatively small circular opening formed therein, a pair of metal balls interposed between the upper edges of said openings and the lower surface of said cover member, and said surface having eight equally spaced downwardly opening recesses formed therein to accommodate portions of said balls, whereby said shaft is releasably restrained in any one of its operative rotary positions.

18. In a multi-position rotary electric switch, in combination, a substantially circular insulating base adapted to be produced by a straight-line molding operation, said base having a centrally located substantially circular main recess and eight equally spaced like auxiliary recesses extending from said main recess to the periphery of said base, a straight-line molded insulating carrier member of circular contour rotatably supported within said main recess, said member having a substantially square central opening formed therein and eight equally spaced upstanding studs formed integrally therewith at the periphery thereof whereby a corresponding number of radial grooves are provided therebetween, a sheet metal member freely insertable within the area defined by said studs, said metal member having an opening symmetrical with respect to and of greater size than said central opening,

said metal member having four lugs formed integrally therewith and projecting outwardly through certain of said grooves, two of said lugs being diametrically opposite to each other and the other two lugs being positioned in the respective notches adjacent one of the lugs first mentioned, and a single combined contact and wiring terminal member positioned in one of said auxiliary recesses and three like contact and terminal members positioned in the group of three auxiliary recesses directly opposite thereto, said lugs being movable from a circuit interrupting position to positions in which the group of three thereof sequentially engage said single contact while said single lug sequentially engages said group of three contacts, whereby three alternative circuits may be completed in sequence or all of said circuits may be interrupted.

19. In a rotary electric switch, in combination, 20 a molded insulating carrier member having a recess formed in one face thereof, said member having an axial opening therethrough of polygonal form in transverse cross section, a metal contactor having a portion of substantially annular form freely insertable into said recess and retained by the walls of the latter in spaced relation to said axial opening, said member having a multiplicity of equally spaced radial grooves extending from said recess to the periphery of 30 the former, said contactor having at least one lug formed integrally therewith and extending through any one of a number of said grooves a substantial distance beyond the periphery of said member, a recessed molded insulating base member 35 within which said carrier is rotatably mounted, and an associated insulating member overlying said contactor to restrain the same and said carrier against outward displacement from said base member.

20. In a rotary electric switch, in combination, 40 a molded insulating carrier member having a recess formed in one face thereof, said member having an axial opening therethrough of polygonal form in transverse cross section, a metal contactor having a portion of substantially annular form freely insertable into said recess and retained by the walls of the latter in spaced relation to said axial opening, said member having a multiplicity of equally spaced radial grooves ex- 45 tending from said recess to the periphery of the former, said contactor having at least one lug formed integrally therewith and extending through any one of a number of said grooves a substantial distance beyond the periphery of said member, a recessed molded insulating base member 50 within which said carrier is rotatably mounted, and an associated insulating member overlying said contactor to restrain the same and said carrier against outward displacement from said base member, said associated insulating member comprising a second like insulating base member superimposed upon and rigidly attached to the base member first mentioned.

21. In a multi-pole, multi-position rotary switch, in combination, a plurality of insulating bases initially of like form and adapted to be produced by a straight-line molding operation, said bases being of substantially circular contour, each base having a centrally located substantially circular main recess and an auxiliary recess of smaller diameter aligned therewith, said auxiliary recess extending downwardly a substantial distance below the main portion of the lower surface of said base and having a relatively thin integral diaphragm forming the bottom wall there-

of, said diaphragm being intact upon the lowermost base and the same having been removed by broaching from the bases thereabove, each base having eight equally spaced auxiliary recesses extending between said main recess and the periphery of the base, a multiplicity of combined stationary resilient contact and terminal members positioned with a press fit in a corresponding number of said auxiliary recesses, the resilient contact portions of said members being located adjacent said main recess, a recessed molded insulating carrier member located within each main recess, a sheet metal member positioned within each carrier recess, each metal member having at least one lug projecting laterally beyond the carrier for movement into and out of engagement with said resilient contact portions, means for rigidly connecting said bases to each other, and a shaft having a portion non-rotatably penetrating all of said carriers to provide for simultaneous rotation of the latter in one direction or the other throughout a predetermined range.

22. In a multi-position rotary electric switch, in combination, a molded insulating base having an imperforate lower surface and a recess in the upper surface thereof, a molded insulating carrier member rotatably supported within said recess, said carrier member having a recess in the upper surface thereof and a multiplicity of equally spaced notches extending radially through the peripheral wall of said last mentioned recess, a sheet metal contactor positioned within said last mentioned recess and having at least one integral lug projecting laterally through a corresponding number of said notches, said insulating base having a multiplicity of equally spaced auxiliary recesses extending from the periphery thereof to said first mentioned recess, a plurality of combined resilient stationary contact and wiring terminal members positioned within certain or all of said auxiliary recesses, the wiring terminal portions of said members acting to seal the respective

auxiliary recesses at the periphery of said base, a resilient insulating gasket of annular form overlying the upper surface of said base adjacent the periphery thereof, a sheet metal cover member overlying said gasket and rigidly attached to said base, a shaft rotatably supported by said cover member, and said shaft having a portion in driving engagement with said carrier and insulated by the latter from said contactor.

- 10 23. In a multi-pole, multi-position rotary electric switch, in combination, a plurality of insulating bases produced in like form by a straight-line molding operation, each base having a main recess and eight equally spaced auxiliary recesses extending from said main recess to the periphery of the base, each base having a plurality of combined resilient stationary contact and terminal members positioned within certain of said auxiliary recesses, the terminal portions of said members being adapted to seal the peripheral openings of the respective auxiliary recesses, a molded, imperforate, rubber-like member positioned within the peripheral portion of each vacant auxiliary recess to peripherally seal the latter, a metal contactor and an insulating carrier therefor rotatably mounted within each main recess, the lower surface of the lowermost base being imperforate and the other bases each having a central opening formed therein by broaching, a metal cover member superimposed upon the upper base of the group, common means for rigidly attaching said bases to each other and to said cover member, a shaft rotatably supported by said cover member and having direct driving engagement with each of said carriers, and a resilient insulating gasket of annular form overlying the upper surface of each base adjacent the periphery thereof, whereby the switching device as a whole is rendered substantially dust-tight.
